US0D1056398S

(12) **United States Design Patent** (10) Patent No.: **US D1,056,398 S**
(45) Date of Patent: ** *Jan. 7, 2025

(54) **CONFECTIONERY**

- (71) Applicant: **ZURU (SINGAPORE) PTE. LTD.**,
Singapore (SG)
- (72) Inventors: **Mathew Peter Mowbray**, Mid-levels
West (HK); **Chung Hyun Lee**, Seoul
(KR); **David Johnston Smith**,
Auckland (NZ); **Diwata Katrina**
Dinglasa Santillan, Auckland (NZ);
Ethan Luke Harrold, Auckland (NZ);
Ethan Hutchinson, Dairy Flat (NZ)
- (73) Assignee: **ZURU (SINGAPORE) PTE. LTD.**,
Singapore (SG)

(*) Notice: This patent is subject to a terminal disclaimer.

(**) Term: **15 Years**

(21) Appl. No.: **29/935,113**

(22) Filed: **Mar. 29, 2024**

(57) **CLAIM**

The ornamental design for a confectionery as shown and
described.

DESCRIPTION

FIG. 1 is a front elevation view of a confectionery showing
our new design;

FIG. 2 is rear elevation view thereof;

FIG. 3 is a top plan view thereof;

FIG. 4 is a front, top, and right-side perspective view
thereof; and,

FIG. 5 is a front, bottom, and right-side perspective view
thereof.

The broken lines shown in FIGS. 1-3 illustrate environment
and form no part of the claimed design.

1 Claim, 3 Drawing Sheets
